G. M. & H. W. CLARK,
AUTOMATIC AIR CAR COUPLING,
APPLICATION FILED FEB. 17, 1913.

1,083,189.

Patented Dec. 30, 1913.

By

Attorney

UNITED STATES PATENT OFFICE.

GEORGE M. CLARK AND HENRY W. CLARK, OF BALL GROUND, GEORGIA.

AUTOMATIC AIR CAR-COUPING.

1,083,189.

Specification of Letters Patent.

Patented Dec. 30, 1913.

Application filed February 17, 1913. Serial No. 749,000.

To all whom it may concern:

Be it known that we, GEORGE M. CLARK and HENRY W. CLARK, citizens of the United States, residing at Ball Ground, in the county of Cherokee and State of Georgia, have invented certain new and useful Improvements in Automatic Air Car-Couplers; and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in automatic fluid pressure couplings for train pipe service and comprises various details of construction and combinations and arrangements of parts which will be hereinafter fully described, shown in the accompanying drawings and then specifically defined in the appended claims.

We illustrate our invention in the accompanying drawings, in which:—

Figure 1 is a central sectional view through two couplers detached, and Fig. 2 is a view showing the couplers connected together and partially in longitudinal section along the line 2—2 of Fig. 1.

Reference now being had to the details of the drawings by letter, A designates a coupler head, two of the couplers being of similar construction, and B designates a fluid pressure pipe which communicates with a central passageway C leading through the coupler head. Said pipe has a coiled buffer spring D mounted about the same and adapted to take up vibrations and cushion the coupler heads when they are coupled together. The coupler head is provided with a chambered portion E, and F is a valve which regulates the passage of the fluid through the pipe, and G is a lever pivoted at H to the band I mounted upon said pipe. Said lever extends forwardly through the chambered portion E and is guided between the posts K, which project from the bottom of said chambered portion. A spring, designated by letter L, is mounted about said posts and bears yieldingly against the outer edge of the lever and serves to throw the same against the bottom of the

chambered portion of the head. The forward end of the said lever is inclined as at N.

Each coupler has a projection O upon its forward end which is beveled as at O' and each projection is adapted to contact with an inclined or beveled portion of the lever for the purpose of throwing the latter outward against the tension of said coiled spring and opening the valve in the pipe. Each coupler head has a deflecting wing R set at an inclination and is adapted to guide the two coupler heads when they come together to be coupled.

The central passageway which leads through the coupler head has a gasket T countersunk in a recess at the forward end of the coupler, the two gaskets of the couplers being adapted to form a tight joint when they come together to be coupled. Bearing plates T' are mounted upon each adjacent end of the coupler and about said gaskets.

The operation of our coupler will be readily understood and is as follows:—When the two coupler heads similarly equipped come together, the projections with beveled portions each coming in contact with a lever will cause the same to open the valve and the valves will be held open, thus making a continuous passageway from one car to another and give a tight joint about the gaskets which come in contact with one another.

What we claim to be new is:—

1. A fluid pressure coupler for train service pipes, comprising a coupling head with a passageway leading therethrough and a chambered portion opening through the ends of the coupler head, a service pipe communicating with the passageway, a valve in said pipe, a lever pivoted upon a standard of said pipe and extending into the chambered portion of the head and connected to the stem of said valve, the forward end of the lever being beveled, a slotted post in said chambered portion of the head through which said lever passes, a spring upon said post and bearing yieldingly against the lever, and a beveled projection upon the coupler head, as set forth.

2. A fluid pressure coupler for train service pipes, comprising a coupling head with a passageway leading therethrough and a chambered portion opening through the

ends of the coupler head, a service pipe communicating with the passageway, a valve in said pipe having a stem projecting through the latter, said stem being slotted, a stand-
5 ard upon the pipe, a lever pivoted thereto and passing through the aperture in said stem and extending into the chambered portion of the head, a slotted post rising from the bottom of the chambered portion and
10 through which said lever passes, the forward end of the lever being beveled, a

spring upon the post bearing against the lever, the forward end of the head having a beveled projection, as set forth.

In testimony whereof we hereunto affix 15 our signatures in the presence of two wit-nesses.

GEORGE M. CLARK.
HENRY W. CLARK.
